UNITED STATES PATENT OFFICE.

GEORGE CHAPMAN, OF KEARNEY, NEW JERSEY, ASSIGNOR TO THE NAIRN LINOLEUM COMPANY, OF KEARNEY, NEW JERSEY, A CORPORATION OF NEW JERSEY.

SHIPPING-CRATE.

1,173,928.

Specification of Letters Patent. Patented Feb. 29, 1916.

Application filed May 14, 1915. Serial No. 28,082.

To all whom it may concern:

Be it known that I, GEORGE CHAPMAN, a citizen of the United States of America, and residing in the town of Kearney, county of 5 Hudson, and State of New Jersey, have invented a certain new and Improved Shipping-Crate, of which the following is a specification.

My invention relates to shipping crates 10 and particularly to crates for handling heavy rolls such as pieces of linoleum, or the like.

The object of my invention is to provide a light yet strong construction which will effectively protect the contained roll and maintain its own condition without danger of destruction during the rough handling commonly experienced in freight shipments.

In the accompanying drawings, Figure 1 20 is a perspective of a crate in which my invention is embodied in one form; Fig. 2 is an end elevation thereof; Fig. 3 is a partial side elevation thereof; Fig. 4 is a transverse section with the detachable halves of the 25 crate separated; Fig. 5 is a perspective of a modification, with the crate sections detached; Fig. 6 is an end elevation thereof with the sections assembled; and Fig. 7 is a cross section with the parts detached.

30 It has been found that when shipping heavy rolls of linoleum in crates of ordinary construction, the latter are very apt to become distorted or even wrecked through the dropping of the crates at an angle on the 35 ends of the longitudinal crate slats. A like result is often produced by the "spinning" of the crate, viz., the rolling of the crate while tilted at an angle, during which its entire weight rests momentarily on the end 40 corners of the successive slats as the crate is rolled or spun to position. Furthermore, the practice heretofore has been to build the crate on the roll, the end heads being solid and the longitudinal slats being nailed in 45 position while the roll is up-ended on one head. This operation is not convenient and moreover is time consuming.

The present construction not only expedites the assembly of the crate on the roll, 50 but also protects the longitudinal slats against end impact during the normal handling of the crate, and injury to the same is thus prevented.

In its preferred form the heads of the 55 crate are polygonal, and in the form shown

in Figs. 1 to 4, they are hexagonal, six slats 10 being used. To expedite the packing of the roll, the crate is made in halves, each head comprising two sections 11 and 12 which meet at the mid-line 13 bisecting opposite angles of the hexagon. Each half of the crate thus forms a cradle into one of which the roll may be placed, the other half being then positioned thereover and secured in position. Cross cleats 14, 15 and 16 are employed for this purpose, two of these viz. 14 and 16 being carried by one head section 12 and spaced apart, while the third cleat 15 is carried by the other head section 11 in central position so that it 60 enters between and interlocks with the cleats 14—16. These cleats are preferably riveted to their respective head sections by long nails 17 the inner ends 18 of which are turned down and clenched against the inner 65 face of the head sections. They lie at right angles to the meeting line 13 of the head sections and extend on the outer face of the head from one margin to the opposite margin thereof. In width they are preferably 70 such that the three cleats together extend transversely the entire width of one side b of the hexagon and in thickness they are preferably at least equal to that of the slats 75 10. Short nails 19 driven into the portions 80 of the cleats which overlap the opposite head sections 11 and 12 hold the halves together and thus prevent the crate sections from 85 parting. The cross cleats not only hold the 90 crate sections together, but also through 95 their interlocking engagement, effectively prevent the halves from being distorted with 100 relation to each other through side strains. It is obvious that the assembly of the crate halves upon the roll may be quickly accomplished, while the driving of the securing 105 nails 19 in the cross cleats is much more conveniently and speedily accomplished than is the building up of the crate upon the roll in accordance with the usual practice above mentioned. A further and most important function of the cross cleats 14, 15 and 16, is the protection which they afford to the ends of the slats 10. It will be noted that the ends of the slats 10 are nailed 110 flush with the outer face of the crate head. The cleats however lie on the outer face of the latter. They also extend the full width of the head between the opposite sides b thereof. Being of a thickness at least equal 115

to that of the slats 10, it is obvious that until the crate is tilted to more than 45° from the perpendicular, its weight cannot rest wholly upon the ends of the slats extending between the sides *b* of the heads at opposite ends of the crate. Impact against the end of the slat when the crate is at a greater angle than 45° has no appreciable distorting or displacing action. These slats are therefore protected against injury from this source. The same is true of the slats attached to the sides *a* and *c* of the head. The angle between the corners 20 of the head and the sides of the cleats 14 and 16 is such that the crate must be tipped a considerable distance from the vertical before it is possible for the ends of the slats attached midway of the sides *a* and *c* to receive the impact. This angle is made the greater by the beveling at 21 of the outer edges of the slats. Furthermore, a short supplemental cleat 22 only one of which is shown in Fig. 1, may be added after the crate sections are assembled, to receive the impact which might otherwise fall upon the corners of these slats. It is obvious that there is no danger of the slats being displaced during the spinning of the crate, since during the latter operation the crate is maintained as nearly vertical as possible in order to relieve the operator of its weight and consequently the cleats 14, 15 and 16 (and 22 when used) and the corners 20 of the head form the points of support as the crate is spun to position.

While the construction described is perhaps the most economical as well as efficient now known to me for effecting the desired result, various modifications of construction will readily suggest themselves. Thus 40 dowels 23 (Fig. 4) carried by the head section 11 may be substituted for the mid-cleat 15 and take into recesses 24 in the edge of the coöperating head section 12. This expedient is more expensive however since it necessitates the affixing of the dowels to one part and the counterboring of the other to receive them.

A third construction, which is efficient, but rather more expensive is shown in Figs. 5-7. The slats 10 and head sections 11 and 12 are the same as in the construction above described. The cross cleats in the present modification however comprise broad boards 25, 26, forming an outer protective head, in two parts, permanently secured respectively to the main head sections 11 and 12 by rivets 27 and projecting in part across the outer face of the other section to which, in the assembled crate, it is attached by 60 means of short nails 28. While the overall diameter of this protective cleat head is the same as that of the main head 11-12, its peripheral shape is that of a duo-decagon instead of a hexagon with the result that its 65 areas 29 project over and thus protect the

ends of the slats 10 from any possible direct impact.

Various other modifications by which the same protection is received will readily suggest themselves which at the same time do not depart from what I claim as my invention.

I claim as my invention:—

1. A shipping crate of the character described, comprising heads, slats extending between the same and having their ends flush with the outer faces of said heads, in combination with cleats on the outer faces of said heads serving to protect the ends of the slats against impact when the crate is dropped on end or at any angle less than substantially 45° from the perpendicular.

2. A shipping crate of the character described, comprising two-part heads, slats extending between corresponding head parts at opposite ends of the crate, to form independent coöperating cradle sections, the ends of the slats having their ends flush with the outer faces of their respective head sections, in combination with cleats on the outer faces of said heads serving in the finished crate to unite said cradle sections and at the same time to protect the ends of the slats against impact when the crate is dropped on end or at any angle less than substantially 45° from the perpendicular.

3. A shipping crate of the character described, comprising two-part heads, slats extending between corresponding head parts at opposite ends of the crate, to form independent coöperating cradle sections, the ends of the slats having their ends flush with the outer faces of their respective head sections, in combination with cleats mounted on the outer faces of the said respective head sections and overlapping and secured to the coöperating head sections in the finished crate, said cleats serving to protect the ends of the slats against impact when the crate is dropped on end or at any angle less than substantially 45° from the perpendicular.

4. A shipping crate of the character described, comprising two-part heads, slats extending between corresponding head parts at opposite ends of the crate, to form independent coöperating cradle sections, the ends of the slats having their ends flush with the outer faces of their respective head sections, in combination with interlocking cleats mounted on the outer faces of the respective head sections and overlapping, in interlocked relation, the coöperating head sections in the assembled condition of the parts, said cleats being secured to both head sections in the finished crate and serving to protect the ends of the slats against impact when the crate is dropped on end or at any angle less than substantially 45° from the perpendicular.

5. A shipping crate of the character described, comprising two-part heads, slats extending between corresponding head parts at opposite ends of the crate, to form independent coöperating cradle sections, the ends of the slats having their ends flush with the outer faces of their respective head sections, in combination with cleats mounted on the outer faces of the respective head sections
- 10 and respectively overlapping and secured to the coöperating head sections in the finished crate, each of said cleats extending completely across the finished head from one margin to the opposite margin.
- 15 6. A shipping crate of the character described, comprising two-part heads, slats extending between corresponding head parts at opposite ends of the crate, to form independent coöperating cradle sections, the ends of the slats having their ends flush with the outer faces of their respective head sections, in combination with cleats mounted on the outer faces of the respective head sections in position to interlock in over-
- 20 25 lapped relation to the respective coöperating head sections in the finished crate, each of said cleats extending completely across the finished head from one margin to the opposite margin.
- 30 7. A shipping crate of the character de-

scribed, comprising two-part heads, slats extending between corresponding head parts at opposite ends of the crate, to form independent coöperating cradle sections, the ends of the slats having their ends flush with the outer faces of their respective head sections, in combination with cleats mounted on the outer faces of the respective head sections and overlapping the respective coöperating head sections in the finished crate, 35 said cleats extending completely across the head from one margin to the opposite margin, for the purpose specified.

8. A shipping crate comprising heads at opposite ends of the crate, slats extending 45 between the same with their ends substantially flush with the outer faces of the heads, and cleats extending between opposite margins of the outer faces of the heads, the peripheral margins of the slats being beveled 50 to prevent end impact thereon during the normal handling of the crate.

In testimony whereof I have signed my name to this specification, in the presence of two subscribing witnesses.

GEORGE CHAPMAN.
